UNITED STATES PATENT OFFICE

EBENEZER A. W. JEFFERIES, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GAS-PRODUCER.

1,198,037.

Specification of Letters Patent. Patented Sept. 12, 1916.

Application filed August 6, 1913. Serial No. 783,320.

To all whom it may concern:

Be it known that I, EBENEZER A. W. JEFFERIES, a citizen of the United States, residing at Worcester, in the county of Worcester and Commonwealth of Massachusetts, have invented a new and useful Improvement in Gas-Producers, of which the following, together with the accompanying drawings, is a specification.

10 My present invention relates to that class of gas producers which comprise a rotatable support for the ashes spaced beneath the body portion of the gas producer, said ash support having a radial arm or scraper resting upon the bottom of the ash support and journaled concentrically with said ash support, with means for holding said radial arm stationary while the ash support revolves beneath it, thereby causing the ashes 15 to be crowded outwardly and delivered from the edge of the ash support.

The objects of my present invention are to provide means for engaging the outer end of the radial arm or scraper and for 25 automatically releasing said scraper, allowing it to rotate with the ash support and thereby interrupt the discharge of ashes from the ash support. I accomplish these 30 objects by means of the construction and arrangement of parts as hereinafter described and set forth in the annexed claims.

Referring to the accompanying drawings, Figure 1 is a side elevation of a gas producer of the class described and embodying 35 means for automatically interrupting the discharge of ashes therefrom. Fig. 2 is a plan view of the ash support and scraper with mechanism for automatically releasing the latter. Fig. 3 is a vertical sectional view 40 of a portion of the gas producer, showing a side view of the apparatus for automatically releasing the ash scraper. Fig. 4 is a detail view of the latching mechanism for stopping the rotation of the ash scraper. Figs. 45 5 and 6 are detached views of the mechanism for automatically releasing the ash scraper, and Fig. 7 shows a modification of the automatic scraper releasing mechanism.

Similar reference characters refer to similar parts in the different figures.

Referring to Figs. 1 and 3 of the drawings, 1 denotes the body portion of a gas

producer inclosing a gas producing chamber and spaced above a rotatable ash support 2 consisting, in the present instance, of a shallow pan into which the ashes are delivered from the body portion of the producer through its open bottom. The ash support 2 is mounted upon rollers 3, 3 and is rotated by a rotating pinion 4 engaging an annular 55 rack 5 upon the ash support. Journaled concentrically with the rotating ash support 2 is an ash scraper 6, resting upon the bottom of the ash support and consisting, in the present instance, of a helical shaped arm 60 having its outer or free end 7 arranged to be engaged by a latch 8 pivoted at 9 upon the lower end of an arm 10 rigidly attached to the fixed walls of the gas producer and extending downwardly toward the ash support. 65 By reason of its frictional engagement with the bottom of the ash support, the scraper 6, when not engaged by the latch 8, rotates with said ash support. The upper end of the latch 8 is connected by a link 70 75 11 with a short arm 12 carried upon the inner end of a rocking shaft 13. Attached to the outer end of the rocking shaft 13 is a lever 14 supporting upon its free end an adjustable counterweight 15. The lever 14 is 80 connected by a link 16 with one end of a lever 17 turning loosely upon a shaft 18 supported in brackets 19 upon the top wall of the gas producer. Journaled upon the shaft 18 is a lever 20 carrying upon one end an 85 adjustable counterweight 21, which is normally supported upon a stop or rest 22 by which the lever 20 is maintained in a horizontal position. The opposite end of the lever 20 is pivotally connected by a link 23 90 with a radial arm 24 attached to one end of a rocking shaft 25. The opposite end of the rocking shaft 25 carries a radial arm 26 in the free end of which is a cam roll 27. 95 Attached to the outer wall of the ash support 2 is a cam 28, said cam roll 27 being arranged in the path of the cam 28 as the latter is carried around by the rotatable ash support 2. Extending upwardly from the rocking lever 20 is a short arm 29, upon the 100 end of which is pivotally supported a pawl 30 having upon one end a small counterweight 31 and provided with an arm 32 which carries thereon an adjustable counter-

weight 33. The lever 17 is provided with a notch 34 adapted to receive the end 35 of the pawl 30 as shown in Fig. 6; upon the operation of the mechanism in the manner hereinafter described.

With the lever 14 in the position shown in Fig. 5, the latch 8 is disposed so as to bring its lower end 36 into the path of the scraper 6, and it will be understood, that if said latch be so held, the advancing end 7 of the scraper will be engaged thereby, causing said scraper to be held from rotation. The continued rotation of the ash support, with the scraper thus held from rotation 15 carries the mass of ashes against the helical side of the scraper, causing such ashes to be pushed outwardly and crowded over the flaring side of the pan.

The subsequent movement of latch 8 into the position shown in Fig. 6 permits the rotation of the scraper 6 with the ash support and consequently interrupts the discharge of ashes from said support. The several movements of latch 8 are controlled by the cam 28 in the following manner: The cam 28 as it is carried around by the rotating ash support will ride over the cam roll 27, depressing the arm 26 and rocking the shaft 25. The rocking of the shaft 25 through the 30 radial arm 24 and link 23 will rock the lever 20 on the shaft 18 from the position shown in Fig. 1 to that represented in Fig. 5, whereby the pawl 30, which it will be assumed, has been caused to occupy the position shown in Fig. 1, will tip over to the right, with its end resting against the extreme end of the lever 17, beyond the notch 34 of the latter, as shown in said Fig. 5. When the cam 28 passes the cam roll 27, 40 the counterweight 21 will reverse the motion of the lever 20, restoring it to the position shown in Fig. 1, allowing the end 35 of the pawl 30 to engage the notch 34 in the lever 17. In this position of the pawl 30, 45 the next passage of the cam 28 over the cam roll 27 will again rock the shaft 25, depressing the arm 24 and again rocking the lever 20 through the link 23 into the position shown in Fig. 6. At this rocking movement of the lever 20, however, the engagement of the pawl 30 with the lever 17 will lift the lever 14 through the link 16, thereby 50 rocking the shaft 13 and, through the radial arm 12 and link 11, rocking the latch 8 into the position shown in Fig. 6. The lifting of the latch 8 into this position permits the passage thereunder of the scraper, provided 55 said scraper is in radial alignment with the cam and arrives adjacent the latch when the latter is in raised position. If such is not the case, as happens when the device is first put into action, the subsequent arrival of the scraper finds the latch depressed, owing to the movement of the cam 28 past the roll 60 27. The depressed latch holds the scraper

stationary until the cam 28 again engages the roll 27, moving the latch into the position shown in Fig. 6 and permitting rotation of the scraper. Thereafter the cam and scraper rotate together, the latch 8 being raised at each revolution to permit the passage of the scraper thereunder. When it is desired to make the scraper effective again to discharge ashes from the support, the operator rocks the pawl 30 toward the left, 70 from the position shown in Fig. 6 to that shown in Fig. 1. When the cam 28 again comes into contact with roller 27, the lever 20 is moved downward as shown in Fig. 5, without carrying with it the lever 17, thereby leaving the latch 8 in position to arrest the rotation of the scraper. During the following rotation of the ash support, ashes are therefore discharged, unless there arises a force tending to move the scraper, sufficient 85 to raise the counterweight 21, the latter being made heavy enough to hold the scraper firmly to its work. Should such a force arise, due to the jamming of a mass of clinker between the scraper and the wall of 90 the support, or to any other cause, the latch is forced upwardly against the action of the counterweight and the scraper continues to rotate until the force is removed. When the cam again comes into contact with the 95 roller 27, the pawl 30 has assumed the position shown in Fig. 6, and the release of the scraper is effected. The interruption to the discharge of ashes continues until the operator again rocks the pawl 30 to the left, 100 when the above described operation is repeated. It will be obvious that more than one cam may be used, so that the interruption to the discharge of ashes, which by the 105 above described apparatus is automatically effected after one revolution of the support, may be effected at shorter intervals.

In the apparatus already described, the release of the scraper takes place at each revolution of the ash support, but in Fig. 7 110 I have shown a slight modification by which the release of the scraper may be effected at longer intervals than a single revolution of the ash support. This modification consists in pivoting upon the shaft 18 a lever 37 having a series of notches 38 in one end, in the present instance three in number, and having its opposite end provided with a pin 39 which extends through a slot 40 formed in the link 16. Capable of sliding in the slot 40 is a block 41, the position of which may be adjusted in the slot 40 by means of a screw 42. The lever 37 is provided with a split bearing which incloses the shaft 18. This bearing is provided with a bolt 43 by 115 which the lever 37 may be clamped upon the shaft 18 to produce a slight friction sufficient to prevent it from being rocked upon the shaft 18 by its own weight. By adjusting the block 41 in the slot 40, the link 16 120 125 130

and lever 14 may be lifted by the engagement of one or more of the notches 38, causing one, two or three revolutions of the ash support to take place before the release of the scraper 6 occurs.

I claim,

1. In a gas producer, a rotating ash support, a scraper capable of rotation with said support, means for checking the rotation of said scraper at will, and means actuated by the rotation of said support for releasing said scraper from said checking means.

2. In a gas producer, a rotating ash support, a scraper capable of rotation with said support, means for interposing a stop in the path of said scraper to prevent its rotation with said support, and automatic means for withdrawing said stop from the path of said scraper.

3. In a gas producer, a rotating ash support, a scraper resting on the bottom of said ash support, means for holding said scraper stationary during rotation of said ash support, and means actuated by the rotation of said ash support for rendering said holding means inoperative.

4. In a gas producer, a rotating ash support, means for crowding the ashes toward the edge of said support, and automatic means for interrupting the action of said crowding means.

5. In a gas producer, a rotatable ash support, a scraper journaled at one end, means for holding its opposite end from rotating with the ash support, and means carried by the rotatable ash support for releasing said scraper.

6. In a gas producer, a rotatable ash support, means for rotating the ash support, a scraper journaled about an axis concentric with the axis of the ash support, means for holding the scraper from rotating with the ash support, and means for automatically releasing the scraper from its holding means, comprising a cam carried by the rotating ash support.

7. In a gas producer, an ash support, means for crowding the ashes toward the outer edge of the ash support, and means for automatically interrupting the action of said crowding means.

8. In a gas producer, an ash support, means for rotating the ash support, means located above the bottom of the rotatable ash support for moving the ashes toward the outer edge of the ash support, and means for automatically interrupting the action of said ash removing means by the rotation of the ash support.

9. In a gas producer, a rotatable ash support, a scraper journaled concentrically with the ash support, a latch pivotally supported by the fixed portion of the gas producer, means for rocking said latch to interpose it in the path of the scraper, and means for

automatically withdrawing said latch from the path of the scraper as the ash support is rotated.

10. In a gas producer, a rotatable ash support, a scraper above the bottom of the ash support and capable of rotating with the ash support, means for holding the scraper from rotating with the ash support, and means for releasing said scraper from its holding means by the rotative movement of the ash support.

11. In a gas producer, a rotatable ash support, a scraper journaled at one end above the bottom of the ash support, a latch for holding the opposite end of the scraper from rotation, and yielding means for holding said latch in engagement with the scraper.

12. In a gas producer, a rotatable ash support, a scraper for crowding the ashes toward the outer edge of the ash support, means for holding the scraper from rotating with the ash support, and means for automatically releasing the scraper by one or more revolutions of the ash support.

13. In a gas producer, a rotatable ash support, a scraper journaled at its inner end, a pivoted latch for holding its outer end from rotating with the ash support, yielding means for holding said latch in engagement with the scraper, mechanism for withdrawing said latch and releasing the scraper, and a cam carried by the ash support for actuating said latch withdrawing mechanism.

14. In a gas producer, a rotatable ash support, a scraper capable of rotation with said ash support, a latch adapted to be interposed in the path of said scraper, automatic means for withdrawing said latch from said path when the scraper is rotated into juxtaposition to said latch, and means for rendering said withdrawing means inoperative.

15. In a gas producer, a rotatable ash support, a scraper capable of rotation with said support, a latch adapted to be interposed in the path of said scraper, automatic means for withdrawing said latch from said path during a predetermined period in the rotation of said scraper, and manually operated means for rendering said withdrawing means inoperative.

16. In a gas producer, a rotatable ash support, a scraper adapted to coact with said support to effect the discharge of ashes therefrom, and automatic means for interrupting the action of said scraper.

17. In a gas producer, a rotatable ash support, a scraper, means for holding said scraper stationary with respect to said support, and automatic means for releasing said scraper.

18. In a gas producer, a rotatable ash support, a scraper bar, journaled concentrically therewith and carried in the bot-

tom thereof, a latch depending in the path of said scraper bar, and automatic means, actuated by the rotation of said ash support, for engaging and disengaging said latch, whereby to intermittently permit the rotation of said scraper bar with said ash support.

19. In a gas producer, a rotating ash support, a scraper bar carried thereby, and in frictional engagement therewith, a latch normally held in the path of said scraper bar, and automatic means for intermittently releasing said latch, whereby the scraper bar is permitted to rotate with the ash support.

15 20. In a gas producer, a rotating ash support, an ash discharging means coöper-

ating therewith, and gravity actuated means for retaining said discharging means in operative position.

20 21. In a gas producer, a rotating ash support, a member adapted to be held stationary with respect to said support, to effect the discharge of ashes therefrom, and means for holding said member stationary, 25 said means adapted to be rendered inoperative when the force tending to rotate said member overcomes the force of gravity acting on said means.

Dated this 31st day of July, 1913.

EBENEZER A. W. JEFFERIES.
